UNITED STATES PATENT OFFICE

2,508,123

ICE CUBE LOOSENING DEVICE

Manfred J. Pollak, Chicago, Ill.

Application May 7, 1946, Serial No. 667,973

5 Claims. (Cl. 219—19)

1

This invention relates to improvements in home appurtenances, and has for an object to provide a meritorious and novel thermal-electric device, particularly advantageous for use in conveniently and economically removing or facilitating the removal of ice cubes and similar, as well as other molded bodies from the so-called "ice trays" generally used in the freezing compartments of automatic refrigerators.

Another equally important object of the invention is to provide a device which, following the removal of molded bodies, especially ice cubes, from a container or forming tray, will receive and retain them in such a manner as to sanitarily maintain and preserve the same and permit of their convenient removal, as and when desired.

Yet another object of the invention is to provide the improved device with means, rendered automatically operable with introduction of an ice cube or other molded body containing tray into said device, for bodily heating the tray to a degree entirely sufficient to cause limited melting of the bodies at their points of contact with said tray and the usual partition walls therein, hence, loosening the bodies with relation to the tray and partition walls allowing them to be freely removed or discharged from the tray.

It is also an object of the invention to provide a device of the stated character having an advantageous and novel form of supporting frame assembly and housing, the same being so constructed that positioning of the housing with relation to the frame assembly may be selectively changed in a manner to effect neat and positive delivery of previously loosened bodies within a received tray into a portion of the housing for temporary storing therein.

A further advantageous and hence, important desideratum of the invention, resides in the provision of frictional electrical contact means within the device housing, in a manner to make positive contact with adjacent portions of a tray engaged therein, their arrangements being such as to cause coursing of an electrical current bodily and evenly through said tray, as well as partition walls which may be therein, thus, effecting a substantially uniform overall though limited heating of the same.

A further aim of the invention is to provide a home appurtenance embodying in its construction not only advantageous and, in consequence, meritorious utilitarian features, but attractive and novel design whereby to render the same

2

desirable as an ornamental adjunct to home equipment.

It is well known that in the artificial freezing of tray contained matters, particularly, ice cubes, in the freezing compartments of automatic refrigerators, considerable annoyance and no little bother is experienced by a person undertaking to remove the frozen or molded bodies therefrom. Various appliances, devices and methods have, heretofore, been devised, produced and worked with a view towards bettering or improving such operations. Insofar as I am aware, however, the need for a convenient, efficient and attractive device or method maintains.

15 In making the above statement, I am not unmindful that, (1) mechanical means for effecting a more or less force applied disjunction and removal of ice cubes or other molded bodies from refrigerator freezing trays or like receptacles **20** have been developed, (2) that heating arrangements and constructions (including electrical) have been proposed and reduced to practice whereby those portions of a tray or like receptacle, plus the usual partition walls commonly **25** employed therein, bondingly contacted by frozen or molded bodies, are heated to predetermined degrees to effect a substantially localized and limited melting and freeing of the same, and (3) that different methods of loosening or separating **30** the frozen or molded bodies from their receiving trays, etc., have been devised, including the simple and well known procedure of flowing hot or warm water over the bottom and sides of a tray, and then over the still joined bodily removed frozen or molded forms and partition **35** walls to free the former.

Such devices and methods are, for the better part, unsatisfactory from the viewpoints of practicability; adaptability of the mechanical and **40** electrical devices to standard types of trays in freezing equipment; economies (loss of goodly portions of the frozen or molded bodies by excessive melting thereof), and/or convenience of removal and storing of the removed frozen or **45** molded bodies for subsequent use, as and when desired.

Through the medium of my invention, herein-after more fully described, there is provided a device whose usage and/or operation will satisfactorily comply with all, plus more of those prerequisites hereinabove mentioned.

The foregoing, as well as other objects, advantages and meritorious teachings of my invention, will be in part obvious and in part pointed **55** out in the following detailed disclosure thereof.

when taken in conjunction with the accompanying drawings, it being understood that the forms of the invention presented herein are precise and what is now considered to be the better modes of embodying its principles, but that other modifications and changes may be made in specific embodiments without departing from its essential features.

In the drawings:

Figure 1 is a front end elevation of my improved device, wherein the housing door which permits of access to the housing interior, is shown in a dotted line open position.

Figure 2 is a horizontal longitudinal section taken on the line 2—2 of Figure 1, looking in the direction in which the arrows point.

Figure 3 is a vertical longitudinal section taken on the line 3—3 of Figure 1, looking in the direction in which the arrows point.

Figure 4 is a vertical transverse section through the device, taken on the line 4—4 of Figure 2, looking in the direction in which the arrows point.

Figure 5 is a fragmentary detail in elevation, of the rear end portion of the device, showing the connection of the set-down transformer casing to its rear end wall, and the spring arrangement for movably retaining and returning the rotatable portion of the supporting frame in and to its normal position, and

Figure 6 is a semi-schematic view of the electrical wiring of the device.

Referring in detail to the drawings, the improved device, generally, comprises a base 1, a housing assembly 2, and a tray receiving and supporting frame 3 within the housing.

The base 1 consists of a body of appropriate shape and size (shown in the drawings as being of substantially rectangular formation), constructed of sheet metal, plastic or other suitable material, marginally flanged to provide end and side walls, portions of which have feet 4 or their equivalents and a more or less medially located well therein in which the lower and adjacent portions of the housing vertical circularly shaped end frames (presently described) are fixedly or stationarily received.

The housing assembly 2 includes, in its construction, a pair of longitudinally spaced and relatively opposed circularly shaped end frames 5 and 6. Said end frames are complementally constructed and sized. They are, in fact, metal or plastic rings of right angularly cross-sectional formation, as is illustrated in Figures 2 and 3 of the accompanying drawings, whose horizontal peripheral portions are relatively inwardly disposed, and whose outer vertical portions constitute abutments or shoulders, the purpose of which will be presently apparent.

Circular end walls 7 and 8, preferably constructed of pressed or molded fiber or plastic material, are snugly and rotatably received in the circular end frames 5 and 6, respectively, and as will be appreciated, serve as front and rear end walls for the housing 2.

The front end wall 7 has a rectangularly shaped opening or way formed in the same, normally closed by a horizontally spring hinged vertically swingable door 9 equipped with a suitable handle 10. The opening, and hence, the door 9, are directly adjacent the forward end of the supporting frame 3 and afford access thereto, i. e., through the front end wall 7.

If desired, words, such as "Insert," "Remove," and "Turn," and an appropriate pointing arrow,

may be presented on portions of the outer side of the wall 7 for furnishing directive instructions to a user of the device, as hereinafter more fully described.

The rear end wall 8 is formed with suitably located ways 11 for receiving electrical conductors therethrough, and with a substantially concentrically located opening receiving a spring pressed push rod type of electrical circuit closing switch 12 therein (see Figures 2 and 3); it being noted in this connection that the push rod 12' of the switch extends for a distance into the housing interior adjacent to and in communication with the rear end of the supporting frame 3.

The housing assembly 2 is completed by a covering of sheet-like material 13 engaged with and about and connected to adjacent portions of the peripheries of the circular end frames 5 and 6. A suitable way is lengthwise formed or provided in the upper portion of said covering in order that convenient access may be had to the housing interior. This opening is normally closed by a cross-sectionally arcuately shaped door 14 of appropriate length and width, the door being hinged at one of its sides, as at 15, to an adjacent portion of the cover 13 and having a handle 16, or its equivalent, on the opposite and free side thereof. Thus, by upward or outward swinging of the door 14, the cover provided way is exposed and allows access to be had to the housing interior.

The tray receiving and supporting frame 3 comprises equi-lengthed inwardly fastened channeled strips 17 disposed longitudinally of and through the substantially medial portion of the housing 2 interior, as is well shown in Figures 3 and 4 of the accompanying drawings. Said strips are supported in transversely spaced horizontal relation within the housing interior in substantially parallelism by means of angle brackets 18 formed or otherwise provided on their opposite ends, which, in turn, are fixedly connected by rivets 19, or other suitable securing means, to adjacent portions of the inner sides of the front and rear walls 7 and 8. Note, at this point, that the normally lower leg or web portions of the strips 17 are of greater widths than the normally upper ones, and that these widths, especially those of the upper strip legs, are sufficient to permit the strips to embraceably slidably receive the adjacent sides of a metal (aluminum or like metal) tray, such as shown in dotted lines and indicated by the numeral 20, therebetween, and so, prevent its vertical displacement or disengagement therefrom, particularly, when the tray is position inverted, in the manner hereinafter more fully described.

Because of the positioning of the strips 17 between the circular front and rear end walls 7 and 8, and their fixed connection to the same, as hereinbefore described, it will be seen and appreciated that longitudinal movement or shifting of said end walls with relation to the horizontal or peripheral portions of their respective circular end frames 5 and 6, will be prevented; also, that the walls 7 and 8 will be so positioned and relatively retained as to ensure free or unimpeded rotation of the same within their respective base 1 stationarily supported end frames.

A sump pan or other receptacle 21 is removably received within the lower portion of the housing 2, as shown in Figures 3 and 4, and is adapted to receive and retain the removed contents of the tray 20, a drain opening 22 being preferably formed in the housing for an obvious purpose.

Right angularly formed spring metal contact devices, identified by the numerals 23 and 23', are riveted or otherwise connected to the inner face sides of the channeled strips 17 in equi-spaced relation (see Figures 2 and 3), and the free portions thereof are disposed so as to have positive rubbing contact with adjacent portions or sides of the metal tray 20 as and when the latter is engaged and supportingly received between the channeled strips 17.

The spring contact device 23', as shown in Figure 6, is of thermal-bimetal construction and is expansible, when heated to a predetermined degree, whereby to transmit thrust to the pin 24 connected to the movable contact member of an electrical circuit breaker 25, for breaking the same and maintaining it broken until the bimetal contact device cools and contracts to its normal or near normal position. Thus, overheating of the tray 20, in the event of failure of the circuit closing device 12 to break circuit after a brief circuit closing operation, will be prevented, as hereinafter more fully described.

At this point, it may be noted that the relative arrangement and electrical connection of the contact devices 23 and 23' on the channeled strips 17 are such that when the diagonally opposed ones thereof are engaged and in rubbing or electrical contact with the adjacent sides of the metal tray 20, electric current will traverse the entire body of said tray. Consequently, the tray will be evenly heated in a minimum of time.

A suitable form of bracket 26 having a peripheral channel or groove 26' therein, is fixedly connected to an appropriate portion of the outer side of the rear end wall 8 and supports thereon a step-down transformer 27. Said transformer is so constructed as to provide an output of low voltage alternating power of large current capacity, which, with flowing through the relatively low metallic resistance of the tray 20, will effect heating of the same. A removable housing cover 28 is preferably engaged over the transformer 27 (see Figures 3 and 5 of the drawings) and with an adjacent portion of the bracket 26 for an obvious purpose; a way being provided in its outer side whereby power input conductors 29 can be connected to the transformer primary winding.

Referring to Figure 6 of the accompanying drawings, which illustrates the electrical circuit for causing heating of the tray 20 when the same is engaged in the channeled strips 17 of the tray supporting frame and by the channeled strip supported contact devices 23 and 23', it will be seen that the electric power input conductors 29 are connected to the primary winding 30 of the transformer 27, and that one side of this circuit has the switch 12 (on-off switch) and the bimetal spring contact device operated circuit breaker 25 connected therein. The transformer secondary winding 31 is connected, by conductors 32, to diagonally opposed spring contact devices 23 on the opposite channeled strips 17. Consequently, the flow of electric current bodily through a metal tray 20 engaged by said diagonally opposed contact devices will be effected, thus, insuring even or uniform heating of the same in a minimum of time.

In order that the tray receiving and supporting frame 3 will be normally retained in the position shown in Figures 1 and 4 of the accompanying drawings, and too, will be automatically returned to such position following its rotation to an inverted position, as when the tray 20 sup-

ported on the channeled strips 17 carried by the front and rear end walls 7 and 8 is turned bottom-side-up preparatory to and during its flash heating to thaw and/or loosen its contents for removal, a contractile coiled spring 33 is connected at one of its ends to an element 34—and in the grooved portion 26' of the bracket 26, and at its other end to an element 35 on an appropriate and near portion of the base 4. With rotation of the frame 3 to an inverted position, the spring 33 is tensioned, thus, when the frame is released, it will be immediately counter-rotated to its initial position. If desired, a suitably placed finger or lug 36 can be fixedly mounted on an appropriate portion of the inner side of the rotatable rear end wall 8, as shown in Figure 4 of the drawings, adapted to engage at predetermined points of its rotation with spaced stops 37 and 37' mounted on the stationary covering 13. With engagement of said lug with the stop 37, the tray supporting frame 3, obviously, will be arranged in its normal or initial position, whereas, with engagement of the lug with the stop 37' the tray will be arranged in an inverted or bottom-side-up position.

In operation or usage of my improved device, an ice cube or other body or bodies containing tray (with or without partition walls) which has been removed from the freezing compartment of an automatic refrigerator, is placed into the housing assembly of the same via the door provided way of the front end wall 7, being slidably received and supported (open-side-up) on the channeled strips 17 of the supporting frame 3. The tray is now moved fully rearwardly into the frame 3, and at or near the rearward limit of such movement, its rear end wall engages and thrusts the push rod 12' of the switch 12 inwardly to close the latter. The end wall door 9 is now closed, hence, retaining the tray in operating engagement with said switch push rod 12' whereby a flow of electrical current through the tray will be effected for heating it in the manner hereinbefore described. At this point, the tray is positioned inverted by engaging the handle 10 of the door 9 and rotating it, along with the end walls 7 and 8 and the tray supporting frame 3, to a point where the lug 36 on the rear end wall 8 abuts the stop 37' on the housing assembly covering 13, i. e., it will be thus moved through an arc of approximately 180°.

During the brief interim, the metal tray 20 will have been bodily heated to a temperature sufficient to melt those portions of the ice cubes or other bodies adjacent and adhering to its walls, as well as to the walls of partitions within the tray, hence, loosening and allowing them to fall from the tray into the pan 21.

When the cover handle 10 is released, the spring pressure normally exerted on the push rod 12' of the switch 12, pushes the tray 20 forwardly of its frame 3 and coincidentally, opens said switch 12, thereby automatically interrupting the flow of electric current to the contacts 23 and the tray 20. Also, the now tensioned spring 33 will function to rotatably return the tray supporting frame 3 and the end walls 7 and 8, along with the tray 20, to normal or initial position within the housing assembly. Thereupon, the emptied tray may be conveniently removed from the device housing assembly.

The ice cubes or other bodies in the pan 21 may be removed therefrom by opening the swinging door 14 of the housing assembly, thus, affording access to the housing interior and the pan.

Because of the lesser widths of the normally upper leg or web portions of the channeled strips 17, it is apparent that when the tray supporting frame 3 is position inverted (arranged bottom-side-up) the loosened cubes or bodies in the tray 20 will be allowed to fall freely therefrom into the pan 21.

Excessive heating or overheating of the metal tray 20 will be positively prevented by means of the thermal bimetal contact device 23'. That is to say, should the contacts 23 be energized for too long a period of time, the circuit breaker 25 would be activated by the bimetal contact device 23' which is in physical contact with the metal of the tray 20, and deflects, snap-like, as the tray temperature rises above a pre-determined degree, thus, opening the primary circuit of the transformer 27.

Whereas, I have hereinbefore described my improved device as being equipped with the step-down transformer for use with alternating electric current, it will be understood and appreciated that said device can, as advantageously, be used with direct electric current by placing a suitable heating element on, over or across the channelled strips 17 and connecting a source of direct current thereto from or through the contact devices 23. In such an arrangement, need for the transformer 27 will, of course, be eliminated. Moreover, the arrangement would permit the use of plastic trays or types of trays other than metal, the bodies of which would be heated by exchange as between the direct current heated element and the tray.

I claim:

1. A device of the character described, comprising a housing, position invertible means within the housing for removably receiving and supporting a tray thereon, contact means in the housing engageable with adjacent portions of the tray when received on said first means, a step-down transformer, a circuit closing means connected to the primary winding of said transformer and arranged in the housing for engagement and operation by the tray when said tray is engaged, to a predetermined extent, with said receiving and supporting means, and the secondary winding of said transformer being connected to certain of said contact means.

2. A device of the character described, comprising a housing, means within the housing for removably receiving and supporting a tray, relatively spaced and oppositely positioned contact means in the housing engageable with adjacent portions of the tray when received on said first means, a step-down electrical transformer, circuit closing means in the housing engageable and operable by the tray when the same is received in a predetermined position on said tray receiving and supporting means, said circuit closing means being connected to the primary winding of said transformer, the outermost and diagonally opposed of said contact means being connected to the secondary winding of said transformer, and thermal circuit breaking means connected to the

primary winding of the transformer operable independently of said circuit closing means, at a predetermined time, by one of said contact means.

3. A device of the character described, comprising a housing, walls rotatable in the end portions of the housing, a tray receiving and supporting frame supported by and between said walls, one of said walls having a way formed therein, a cover for the way thrustingly engageable with an adjacent end of the tray, contact means on the frame engageable with adjacent side portions of the tray when received on the frame, and electrical power supply means connected to said contact means.

4. A device of the character described, comprising a housing, walls rotatable in the end portions of the housing, a tray receiving and supporting frame supported by and between said walls, one of said walls having a way formed therein, a cover for the way thrustingly engageable with an adjacent end of the tray, contact means on the frame engageable with adjacent side portions of the tray when received on the frame, electrical power supply means connected to said contact means, and a circuit closer on one of said end walls extending within said housing engageable by the tray when received on said tray receiving and supporting frame, said circuit closer being connected to said electrical power supply means.

5. A device of the character described, comprising a housing one portion of which is open, means for normally closing said open portion of the housing, walls rotatably received and mounted in spaced relation in said housing, a frame fixedly supported by and between said walls for removably receiving and supporting a tray thereon, one of said walls having a way formed therein communicable with said frame, a cover for said way thrustingly engageable with an adjacent end of the tray, relatively spaced and opposed contact means on the opposite sides of said frame engageable with adjacent portions of the tray, circuit closing means carried by one of said walls extending into the housing operable by the tray upon thrusting engagement of said cover with said adjacent end of the tray, and a step-down electrical transformer, the primary winding of said transformer being connected to said circuit closing means and its secondary winding connected to certain of the contact means on the opposite sides of said frame.

MANFRED J. POLLAK.
